UNITED STATES PATENT OFFICE.

THOMAS L. WHITACRE, OF EAST ROCHESTER, OHIO.

WRENCH FOR WAGON-AXLE NUTS.

SPECIFICATION forming part of Letters Patent No. 284,521, dated September 4, 1883.

Application filed February 23, 1883. (Model.)

To all whom it may concern:

Be it known that I, THOMAS L. WHITACRE, of East Rochester, in the county of Columbiana and State of Ohio, have invented a new and 5 Improved Wrench for Wagon-Axle Nuts, of which the following is a full, clear, and exact description.

The object of the invention is to so construct a wrench for turning the axle-nut of a vehicle 10 that it may be hung by a hook in such a manner as to throw the nut-holder out of a perpendicular plane, and thus prevent the nut from dropping out. I effect this by placing a hook and hand-piece on opposite sides of the 15 handle end, so that the weight of the hand-piece will throw the nut-holding end forward out of a perpendicular line, as shown in the drawing.

Reference is to be had to the accompanying 20 drawing, forming a part of this specification, in which a perspective view of my improved wrench for wagon-axle nuts is shown.

The key or wrench A is provided at one end with a squared socket or aperture, B, for receiving the nut, and at the opposite end with a hook, C, projecting from the shank of the key in the same direction as the nut-socket. At the hook end the shank is also provided with a handle, D, projecting in the inverse direction of the hook, which handle is free to 25 turn on its longitudinal axis. If a nut is to be loosened from a wagon-axle to remove the

wheel, the nut is passed into the aperture B, and the key or wrench is turned by means of the handle D until the nut is removed, the 35 nut remaining in the squared socket B. The key is then hung on a rod, E, or any other part of the vehicle, by means of the hook C, which gives the key such an inclination or pitch that the nut cannot fall out of the socket. 40 After the axle has been greased and the wheel replaced the nut can easily be screwed on the axle by means of the key. The nut can be screwed on and off by using one hand only, the fingers and hands are not soiled, the nut 45 need not be placed on the ground, and thus is not apt to get coated with sand and dirt, and the wrench and key are not apt to be dropped.

In using the keys or wrenches of the usual construction the nut and key have to be laid 50 down after the nut has been removed, and in doing so the nut is apt to drop from the key and get sandy, which sand cuts the axle.

Having thus fully described my invention, I claim as new and desire to secure by Letters 55 Patent—

A wrench having the nut-socket B at one end and on opposite sides of the other end, the hook C, and hand-piece D, as and for the purpose specified.

THOMAS L. WHITACRE.
